CLAIM

We claim the ornamental design for a television receiver with rollable display screen, as shown and described.

DESCRIPTION

FIG. 1 is a perspective view of a television receiver with rollable display screen shown in an open position with the display screen unrolled;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view of the television receiver with rollable display screen of FIG. 1 shown in a closed position with the display screen rolled down;

FIG. 9 is a front elevation view thereof;

FIG. 10 is a rear elevation view thereof;

FIG. 11 is a left-side elevation view thereof;

FIG. 12 is a right-side elevation view thereof;

FIG. 13 is a top plan view thereof; and,

FIG. 14 is a bottom plan view thereof.

The broken lines illustrate portions of the television receiver with rollable display screen that form no part of the claimed design.

1 Claim, 14 Drawing Sheets
